J. R. WATKINS, OF MAINE PRAIRIE, MINNESOTA.

Letters Patent No. 79,524, dated June 30, 1868.

IMPROVED CLOTHES-DRIER.

The Schedule referred to in these Letters Patent and making part of the same.

TO ALL WHOM IT MAY CONCERN:

Be it known that I, J. R. WATKINS, of Maine Prairie, in the county of Stearns, and State of Minnesota, have invented a new and improved Clothes-Drier; and I do hereby declare that the following is a full, clear, and exact description of the construction and operation of the same, reference being had to the annexed drawings, making a part of this specification, in which—

Figure 1 is a perspective view.

Figure 2 is a cross-section.

The object of this invention is to furnish to the public a simple, cheap, and durable device for confining and holding the arms of a clothes-drier, and for supporting the same from the vertical walls of the room or building where the instrument is in use.

In the drawings, A is a plate, of cast iron or other suitable material, of the form shown in fig. 1, and provided with a lug, B, cast upon or near its lower end, a cruciform slot, C, near its upper extremity, and screw-holes, D D, by which to fasten it to any vertical wall, E.

F is a lug, similar in shape to the lug B, and directly above it, which is capable of working up and down, in connection with the slot C, by means of a screw-rod, G, having a nut, H. It is held in the slot by means of a head, m, attached to its inner side by a neck or shank, n.

The head can be inserted at the arms of the the cross, and then, if the lug be slipped up or down, it will be impossible for it to become detached, as the head can be withdrawn only at the wide part, or arms, of the cross, where it had been introduced.

The manner of thus attaching the lug to the plate, so that it will be held securely, and yet be capable of vertical movement, will be clearly understood by a glance at fig. 1.

The rear side of the plate A is made sufficiently concave to allow the head m to move freely up and down without coming in contact with the wall.

In practical operation, the plate A is screwed to the wall, where the clothes-drier is to be used, the nut H is unscrewed, and the upper end of the rod G removed from the lug F. The arms of the clothes-drier represented by the red lines of fig. 2 are then inserted upon the rod, one above another, and radiating in different directions. The rod is then inserted into the lug again, and the screw-nut placed on it and screwed down, forcing the lug F down upon the arms, and clamping them rigidly between the two lugs, in which position the device is ready for use.

Having thus described my invention, what I claim as new, and desire to secure by Letters Patent, is—

1. The plate A, having the concave rear side, and provided with the cruciform slot C, screw-holes D D, and the lug B, substantially as and for the purpose set forth.
2. In combination with the above, the screw-rod G, nut H, and lug F, having the head m and shank n, substantially as described.

J. R. WATKINS.
